UNITED STATES PATENT OFFICE

2,583,860

MACHINE FOR FOLDING CARTONS

David Levkoff, Great Neck, N. Y.

Application September 16, 1948, Serial No. 49,543

8 Claims. (Cl. 93—49)

1

This invention relates to a machine for folding cardboard box blanks and setting up or erecting the walls of the box into position for receiving the articles or goods to be packed in the box. The invention has particular reference to tray-like boxes or containers, examples of which are shown in U. S. Patents Nos. 2,274,714 and 2,342,551 although the mechanism to be hereinafter described is readily applicable to and useful in connection with, operations upon boxes of other construction.

An object of the present invention is to provide means by which a plurality of box blanks in collapsed or flat form are successively removed from the bottom of the stack and are moved by suitable conveyor mechanism toward end-folding means where the end and side walls of the box are erected or folded upwardly to vertical position and have flaps downturned and tucked into slits located at the junctions of the box bottom and end walls.

The invention contemplates the provision of means by which the above operations are speedily and effectively performed and the erected boxes rapidly dispensed from the machine.

These and other objects are attained by the invention, a more particular description of which will hereinafter appear and be set forth in the claims appended hereto.

In the accompanying drawings, wherein an illustrative embodiment of the invention is disclosed, Fig. 1 is a front elevation of a machine constructed in accordance with the invention, with the stack-holder and adjacent parts omitted from this view to simplify the disclosure; Fig. 2 is a top plan view of the machine; Fig. 3 is a side elevational view of the machine with certain parts thereof omitted to more clearly show the drive means and conveyor course; Fig. 4 is a side view of the front end of the machine; Fig. 5 is a diagrammatic view of the folding fingers showing the same in the act of erecting the end walls of the carton or tray; Fig. 6 is a similar view, showing the fingers folding down the locking flaps and causing the same to be tucked into the slits in the bottom of the carton; Fig. 7 is a top plan view of the collapsed or flattened carton; Fig. 8 is a view looking at the bottom of the flattened carton, and Fig. 9 is a perspective view in section of the erected carton, showing one of the end walls in its up-standing position.

The box which is erected by the improved machine, is disclosed in detail in Figs. 7, 8 and 9, and the operation of the machine will be more

readily comprehended when the construction of the box and the blank from which it is formed, is fully understood.

The box blank in its flattened condition and as supplied to the machine for erection, is shown at 1 in Fig. 7 and in the form shown it is of tubular form, the bottom of the box or tray which the blank forms, being shown at 2. The opposite face of the blank is centrally and longitudinally split at 3 to form the two panels 4 and 5 which are subsequently raised or erected to vertical position, as shown in Fig. 9 to form the side walls of the box or tray. It will be noted that the lengthy slit 3 connects with curved transverse slits 6, the ends of these slits meeting the ends of score lines 7. Score lines 8 also extend across the panels 4 and 5 at the points clearly seen in Fig. 7.

Located beyond the score lines 8 are the end walls of the box, said walls including the locking flaps 9, transversely scored at 10 and slit through the central portion of the score line as indicated at 11. The bottom 2 of the box has the flaps 12 at its opposite ends, said flaps being provided with the transverse score lines 13. The bottom 2 of the box is also transversely scored as at 15 and also slit on these score lines as indicated at 14. Said slits 14 are intended to receive the ends of the locking flaps 9 when the box is erected, as shown in Fig. 9. To erect the box blank, the same is folded upwardly upon the score lines 15, and this upward folding movement of the opposite ends of the blank causes the panels or box side walls 4 and 5 to fold outwardly or away from one another on the angular score lines 7, and also on the score lines 8. When the side walls 4 and 5 reach their vertical position, it will be found that they have raised the opposite ends of the box, consisting of the parts of the box blank located beyond the fold lines 15, to a substantially vertical position. To maintain all of the four walls of the box in vertical position, the locking flap 9 is folded downwardly upon the fold line 10 to have its free end tucked or inserted in the slit 14 in the bottom 2. When this is done, the walls of the box assume and retain the box in a rigid tray-like form in readiness to receive its contents. After the box is filled, a wrapping of transparent material is usually placed around it, the same holding the end flaps 12 infolded over the top of the contents of the box.

In the apparatus shown in the accompanying drawings, the box blanks, in the flattened condition shown in Fig. 7 are maintained in a stack

from the bottom of which they are successively removed by a chain conveyor operative below the stack, and which removes the blanks from the bottom of the stack and transports them to folding means which folds the end walls to an erect or upright position, and which movement serves to simultaneously fold the side walls also to an upright position. The folding means includes a pair of pivoted fingers which swing toward one another and enter into the box and fold down the locking flaps 9 at the opposite ends thereof and cause said locking flaps to be tucked into the slits 14 provided in the bottom 2 of the box.

The machine is provided with a lower frame having sides including supporting legs 41 and 42, connected and braced by members 43 and 44. Suitably supported in the lower frame of the machine is an electric motor 46, the shaft of which carries a pulley 47 about which a belt 48 extends. Said belt 48 extends about a pulley 31a rotative on a shaft 40 carried in the bracket 49 suitably supported from the top portion of the frame. A pulley 53 is connected to pulley 31 or driven thereby, and pulley 53 is engaged by a belt 54 which extends upwardly and around a pulley 55a on the shaft 56 of reducing gearing assembly contained in the housing 47 suitably supported in the frame of the machine and surrounded by the upper frame members 55. The reducing gearing includes a sprocket 48 engaged by the chain 19 which extends toward the front of the machine and passes around a sprocket 20 secured on cam shaft 21, rotatively mounted in bearings 60 in the upper side frames 55 of the machine.

Secured on the cam shaft 21 are the spaced-apart sprockets 22, around which the conveyor chains 23 extend, said conveyor chains extending upwardly and being in mesh with upper sprockets 24 rotatively mounted upon an upper shaft 25 located above the cam shaft 21. The conveyor chains then extend rearwardly over idler sprockets 26 rotatively supported by brackets 32, and continue rearwardly to pass around sprockets 27 on shaft 28, extending therefrom to the sprockets 22. The chains 23 are thus endless chains constituting conveyor chains and these chains carry, at suitably spaced intervals, lugs 31 which engage the flattened cartons in the stack and successively remove the same from the bottom of the stack and carry them toward the front end of the machine to the folding devices which fold the ends of the boxes to an erect or upright position and tuck the locking flaps 9 into the slits 14.

The stack of flattened box blanks 1, and in which the blanks in the form shown in Fig. 7 are placed on top of one another, is shown at 34 in Fig. 3. The cartons, in such flattened form, are maintained in properly stacked alignment by means of end guides 35 and 36 having flanges 37, (Fig. 2) and front guide plate 37a, these parts being preferably adjustable to enable cartons of various lengths to be accommodated in the stack. The stack support includes also, a base plate 33 upon which the stack of cartons is rested. Said base plate is formed with an inclined forward end 38 and is slotted as indicated at 39, to permit the entry of the conveyor chain lugs 31 to enable the lugs to engage against the edge of the lowermost box blank in the stack and slide it forwardly and off the bottom plate 33 and down the inclined forward portion thereof, and move it toward the forward portion of the machine where the folding devices are located.

While each carton blank is being thus moved forwardly by the conveyor chains 23, it is supported flatwise upon suitable rails such as indicated at 60, 61, 62 and 63, these rails constituting part of the upper framework of the machine. Means may be utilized to hold the cartons down flatly on these supporting rails, such means consisting of flat spring rollers, or similar pressure-imposing elements, such as for example, upper 5 guide bars, one of which is shown at 64 in Figs. 3 and 4. Such guide bars are suspended on rods 65 adjustably dependent from clamps 66 secured on cross rods 67 and 68. Cross rods 67 and 68 are secured between the horizontally disposed frame members 69 supported by uprights 69a as clearly seen in Figs. 1 and 2.

As the flattened carton blanks are carried forwardly along the rails 60 to 63 inclusive by the conveyor chains 23, the end wall portions of the cartons may be initially upwardly bent or folded, 20 and this can be done by guide plates disposed along the ends of the cartons, one of said plates being shown at 70 in Fig. 3, the same being mounted at the end of the rod 71 carried by the clamp 72 on cross rod 67. The result of this arrangement is to fold the carton blank preliminarily on the fold lines 15 and to also cause the two flaps 9 and 12 at the opposite ends of the carton to be folded inwardly. This preliminary folding action 25 of the end portions of the carton, occurs before the carton reaches a pair of plate-like supports 73 and 74, one of which is shown in Fig. 2, and there being a similar one located at the opposite side of the machine.

These plate-like supports are each provided with a downwardly inclined end portion 75 (Fig. 4) which facilitates the disposition of the carton blank on them, and when passing over these supports 73 and 74, the end portions of the blank pass under pressing rollers 76 and 77 supported by the arms 75a suspended from cross bar 68. Said rollers 76 and 77 flatten down the infolded flap portions 9 and 12 at the opposite ends of the carton. The carton is next engaged at its rear edge by a pair of fingers 78 consisting of the upwardly directed ends of a yoke 79, which engages against the rear edge of the carton and moves it forwardly into folding position.

The yoke 79 on which the fingers 78 are formed, 50 has a hub which is rockingly mounted on the shaft 25, and it includes a downwardly extending cam lever 80, carrying the cam roller 81, maintained in contact with the edge of a cam 82 secured on the cam shaft 21. Springs or other known means for holding the roller 81 in contact 55 with the edge of the cam 82 may be utilized, such known means being omitted from the drawing to simplify illustration.

Also secured on the cam shaft 21 is a cam 83 and against the edge of the same is located the cam roller 84 at the end of the arm 85 which forms a downward extension of the hub of a carton-restraining yoke 86, having the upturned ends or fingers 87, which engage against the forward edge of the carton and hold it against forward movement while the walls and ends of the carton are being folded to an erect position. The roller 84 may also be maintained against the cam 83 by springs not shown. The parts described 60 are so arranged and their action is so timed that when the carton is moved forwardly from under the rollers 76 and 77, it will reach a position below the folding fingers 88 and 89 where it will become located between the restraining elements 75 78 and 87 and held thereby stationary for a dwell

or predetermined period of time during which the folding upwardly or erection of the walls and ends of the carton occurs.

Each of the folding fingers 88 and 89 includes a downwardly-bent end or extremity 90 terminating in a rounded tip 91, said end portion being preferably adjustable on the body of the finger to compensate for cartons of different length. The body of the finger 88 is pivoted at 92 between the walls of an adjustable support 93, 10 adjustably mounted on a supporting bracket 94 fastened to one of the side frames 55. An adjusting screw 95 permits the bracket 93 to be moved as required to enable the machine to operate upon cartons of various lengths.

The finger 88 is pivotally attached at 96 to the upper end of a pitman 97 which has its lower end attached by a ball-and-socket connection 98 to a pin 99 at the end of a crank 100 secured on the cam shaft 21. At the opposite end of the cam shaft 21 is a crank 101 which has its pin 102 attached with a ball-and-socket connection 103 to the lower end of a pitman 104 which has its upper end connected at 105 to the folding finger 89. Said finger 89 is pivoted at 106 between the walls of an adjustable support 106 adjustably mounted on the bracket 107 attached to the second side frame member 55. The screw 95a enables adjustment of support 106 to be readily made. It is to be noted that the ends or tip portions 90 of the two folding fingers 88 and 89 are to one side of the central longitudinal line of the body of each finger so that these two tips may pass one another to enter into the carton and simultaneously fold down the two locking flaps 9 thereon and cause the same to be tucked into the two slits 14.

Pivotedly mounted on each of the pivot pins 92 and 106 respectively is an arm 108 carrying a face plate 109 which engages one of the ends of the carton and folds it upwardly as the finger 88 or 89 on which said arm 108 is carried is swung down over the top of the carton. The arm 108 is pivotally attached to the end of a link 110 which extends slidably through the body of the finger 88 or 89. The arm is spring-pressed by spring 111.

From the foregoing, the operation of the device will be readily understood. Cartons in flattened form are contained in the stack 34 as previously disclosed, and are successively carried from the bottom of the stack and moved along the rails 60 to 63 inclusive toward the folding fingers 88 and 89. While being so moved, the ends of the cartons may, if necessary, be preliminarily flexed at the transverse score lines 15 and at the flap-folds 10 and 13, to facilitate the later folding or erection of the cartons at these points. When each carton reaches the rollers 76 and 77, the flaps 9 and 12 are flattened down thereby, and then the carton reaches a point below the folding fingers 88 and 89. At this time, the restraining fingers 78 and 87 are moved up to become positioned at the opposite side edges of the carton and hold it stationary for a predetermined time. While the carton is being so held or restrained, the two fingers 88 and 89 are swung inwardly or toward one another, and as such inward movement of these elements 88 and 89 occurs, the resiliently mounted pressure plates 109 engage against the opposite ends of the carton and start to fold these ends upwardly on the fold lines 15 in the manner diagrammatically shown in Fig. 5. This upward movement of these opposite ends of the carton causes a simultaneous upward

movement of the side walls 4 and 5 of the carton so that the four walls of the carton are thus simultaneously brought to an erect position. As further downward movement of the folding fingers 88 and 89 continues, the tips or extremities 91 of the fingers will enter the carton and contact with the locking flaps 9 at the opposite ends of the carton, folding these flaps 9 downwardly and causing them to enter into the slits 14 in the bottom of the carton. This is diagrammatically shown in Fig. 6. As the fingers 88 and 89 enter the carton the flaps 9 and ends of the carton are compressed between the ends 91 of these fingers and the resiliently-supported pressure plates 109, the latter backing up the ends of the carton and holding them upright while the flaps 9 are folded down and are tucked into slits 14.

At the conclusion of the operations above described, the fingers 88 and 89 are swung back or elevated and they thus rise out of the erected carton. The timing of the machine is such that when this occurs, the restraining fingers 78 and 87 are swung downwardly to free the carton, and at this time ejector fingers 115, carried by the hubs of the sprockets 24, swing around into contact with the rear edges of the erected carton and move it forwardly and away from the folding fingers where it can be manually picked up or directed into a slide or chute and thence into a collection receptacle at the front of the machine.

The structure described is such that the folding and erection of the cartons takes place with speed and accuracy and each carton is uniformly erected. While I have herein suggested that the cartons upon which the machine operates shall be those in which the ends are provided with locking flaps tucked into slits, it will be apparent that the machine may be utilized for the erection of cartons of other construction, hence in describing the operation of the machine in connection with a special type of carton, I do not wish to be understood as limiting the invention to the use of such carton.

While I have described one embodiment of the invention, it is obvious that the same is not to be restricted thereto, but is broad enough to cover all structures coming within the scope of the claims appended hereto.

What I claim is:

1. In a machine of the character described, means for supporting a carton stack, a chain conveyor for successively removing cartons from the bottom of the stack and carrying the same away from the stack, means for engaging each carton so removed from the stack and holding it for a predetermined period in a stationary position, pivoted tucking fingers located at each end of said carton-holding means, means for pivotally moving said pivoted tucking fingers, resiliently mounted plates carried by said fingers for engagement with the ends of the carton while the carton is held stationary to fold said ends upwardly to erect position, and end portions on the fingers caused to enter into the erected carton and fold downwardly flaps on the ends of said carton and cause said flaps to be tucked into slits provided in the bottom portion of the carton, each finger folding down the flap at that end of the carton that is held in erect position by the resiliently-mounted plate of its companion finger.
2. In a machine of the character described, means for supporting a stack of flattened cartons,

carton-folding means, a conveyor for removing successive cartons from the bottom of the stack and conveying the same successively to the carton-folding means, carton-holding means located at the folding means for holding each carton in a stationary position for a predetermined period of time, the carton-folding means including parts movable toward the opposite ends of the carton to engage said ends and fold the same to an upright position while the sides of the carton are simultaneously moved to an erect position, said carton-folding means including swinging fingers pivotally moved toward and crossing one another and brought down inside of the carton and against flaps located on the ends of the carton to thereby fold down said flaps and cause the same to be tucked into slits provided in the bottom of the carton, each finger folding down the flap on that end of the carton which is held upright by the parts carried by and movable with its companion finger.

3. In a machine of the character described, a support for a flattened carton, means engaging the opposite side edges of said carton to hold the carton from shifting movement, a pair of pivoted fingers movable toward one another to enter into the carton to engage flaps at the opposite ends of the carton to fold down said flaps into the carton and cause the flaps to enter slits provided in the bottom of the carton, and resilient means carried by said fingers and capable of movement independently thereof for engaging the opposite ends of the carton to raise said ends to upright position before the fingers enter into the carton, the resilient means carried by one finger acting to raise the end carrying the flap that is tucked in by the other finger.

4. In a machine for setting up cartons, means for conveying flattened cartons, means for halting said cartons at a predetermined point, means at said point for holding the carton against movement, means operative at the opposite ends of the held carton for folding up the ends of the carton to upright position, said means including resiliently-mounted pressure plates, fingers on which said plates are resiliently mounted, said fingers having end portions entering into the cartons and folding down flaps thereon into the carton to locked positions while the ends of the carton are held by the pressure plates in upright position, the plate on one finger supporting a carton-end while the flap on said end is folded down to locked position by the other finger.

5. In a machine for setting up cartons of the type having locking flaps tucked in slits at the opposite ends of the cartons, means for supporting a flat carton blank in a stationary position, pivoted tucking fingers located at the opposite ends of the support and adjacent to the locking flaps of the carton held on the supporting means, means for pivotally swinging said fingers toward one another and causing them to cross each other in their arcs of swing to enter the supported carton in such crossed relation, each of the tucking fingers having a resiliently-mounted plate for contacting with an end portion of the carton and elevating said end portion to an erect position, the resiliently-mounted plate on one of the fingers elevating the end of the carton carrying

the locking flap that is tucked in by the other finger.

6. In a machine for setting up cartons having folded-down locking flaps tucked in slits at the opposite ends of the carton, a support for each carton while it is being set up, a pair of tucking fingers respectively pivoted at the opposite ends of the support, means for swinging said fingers and causing the same to cross one another in their pivotal movement toward one another, each finger carrying a resilient member for engaging the end of the carton located nearest to its pivot and elevating said end to an erect position, the fingers each having an extremity entering into the carton when said fingers are in crossed relation to engage the locking flaps at the ends of the carton and tuck the same in the slits, the extremity of each finger engaging the locking flap remote from the end of the carton that is elevated by the resilient member carried by that finger.

7. In a machine for setting up cartons of the type having folded-down locking flaps tucked in slits at the opposite ends of the carton, conveying means for successively engaging and carrying cartons in a substantially flat condition, means for halting and supporting each carton so carried, a pair of fingers respectively pivoted at the opposite ends of the supporting means, means for pivoting said fingers toward one another and causing them to cross one another in such pivotal movement, said fingers having means engaging the opposite ends of the halted and supported carton and folding said opposite ends to upstanding position, said fingers having extremities entering into the carton when the fingers are in crossed relation so that the extremity of each finger engages and folds down a locking flap farthest from the pivot of said finger.

8. In a machine for setting up cartons of the type having folded-down locking flaps entering into slits at the opposite ends of the carton, means for supporting a carton blank in a stationary position, pivoted tucking fingers located at the opposite ends of the support and adjacent to the locking flaps of the carton held on the supporting means, means for swinging said tucking fingers toward one another and causing the same to cross one another in their swing, a resiliently mounted plate carried by each finger for contacting with opposite end portions on the blank and folding said end portions to upstanding position, said tucking fingers being provided with extremities entering into the carton and folding down the locking flaps thereon and causing the same to enter the slits in the carton, the extremity of one finger being operative to fold down a locking flap at the end of the carton that has had its end portion raised by the resiliently mounted plate of the other finger.

DAVID LEVKOFF.
